(57) **CLAIM**

The ornamental design for a modular cap, as shown and described.

DESCRIPTION

FIG. 1 is a front view of the modular cap in accordance with my design;

FIG. 2 is a rear view of the modular cap shown in FIG. 1;

FIG. 3 is a left side view of the modular cap shown in FIGS. 1-2;

FIG. 4 is a right side view of the modular cap shown in FIGS. 1-3;

FIG. 5 is a top view of the modular cap shown in FIGS. 1-4;

FIG. 6 is a bottom view of the modular cap shown in FIGS. 1-5;

FIG. 7 is a cross sectional view of the modular cap shown in FIGS. 1-6 taken along line 7—7;

FIG. 8 is a top view of the modular cap shown in FIGS. 1-7 when in use;

FIG. 9 is a top view of the modular cap shown in FIGS. 1-7 in an alternate state of use;

FIG. 10 is a front view of the modular cap shown in FIGS. 1-7 in use as attached to a wall hanger;

FIG. 11 is a right side view of the modular cap shown in FIGS. 1-7 in use as attached to a wall hanger;

FIG. 12 is a front view showing the wall hanger of FIGS. 10-11 for attaching the modular cap;

FIG. 13 is a right side view showing the wall hanger of FIGS. 10-12 for attaching the modular cap; and,

FIG. 14 is an enlarged right side view of a side fastener of the wall hanger shown in FIGS. 10-12 for attaching the modular cap.

The broken lines showing a visor and a zipper in FIGS. 1-7, two visors, a zipper and a second modular cap in FIG. 8, a zipper, a visor and a second modular cap in FIG. 9, a wall hanger in FIGS. 10-13, five visors and zipper pulls in FIG. 10, five fastening structures in FIG. 11, and a single fastener in FIG. 14 illustrate environmental matter and form no part of the claimed design.
